ELECTRIC SNAP SWITCH

George J. Meuer and William C. Stevens, Milwaukee, Wis., assignors to Cutler-Hammer, Inc., Milwaukee, Wis., a corporation of Delaware

Application May 16, 1931, Serial No. 537,774

30 Claims. (Cl. 201—48)

This invention relates to improvements in electric snap switches.

An object of the invention is to provide a snap switch of extremely small dimensions the parts of which may be readily and quickly assembled.

5 Another object is to provide novel mounting means for the switch mechanism as a whole.

Another and more specific object is to provide a novel form of snap switch for attachment to 10 and for cooperation with a radio rheostat or similar electrical device.

Another object is to facilitate assembly of the movable switch parts with respect to each other and with respect to the insulating supporting base.

15 Another object is to provide stationary and movable switch contacts of improved form.

Other objects and advantages of the invention will hereinafter appear.

The accompanying drawing illustrates an embodiment of the invention which will now be described, it being understood that the embodiment illustrated is susceptible of modification without departing from the scope of the appended claims.

In the drawing, Figure 1 is a perspective view, 25 in separated relation, of the switch parts and the insulating supporting base therefor.

Fig. 2 is a top plan view of the assembled switch parts in the circuit breaking position thereof.

Fig. 3 is a sectional view on the broken line 30 3—3 of Fig. 2.

Fig. 4 is a side elevation, with parts broken away, showing our improved switch mechanism attached to a radio rheostat of well known form.

Fig. 5 is a bottom plan view of the metal cover 35 member of the rheostat showing the switch mechanism attached thereto—certain other parts of the rheostat being shown in section and in dotted lines, and

Fig. 6 is a plan view of the rheostat and switch mechanism in completely assembled relation. 40 This figure shows the normal size of the switch and rheostat parts—the other figures showing the parts enlarged to different degrees for clarity of illustration.

45 Referring to the drawing, the numeral 10 designates an extremely shallow base which may be molded from any suitable insulating material. We prefer to form this base of the phenol formaldehyde condensation product known as "Bakelite." Base 10 is provided with a relatively shallow recess 11 which extends throughout the major portion of one surface thereof,—thus providing a surrounding wall of substantially uniform thickness or width, except at the diagonally opposed 50 corners 13 and 14 which are pierced as at 13a and

14a to accommodate suitable attaching elements. Also as shown a portion 12a of the wall at one end of base 10 is of increased height to correspond with the particular form of the metal cover member to which the base is to be attached. 5

The bottom wall of recess 11 is pierced at spaced points 15 and 16, the portion 12a of the surrounding wall being widened to provide an arcuate surface 12b concentric with opening 15, said surface 12b having at each side thereof vertical 10 shoulders 12c and 12d the planes of which are radial to said opening 15. The movable parts of the switch mechanism comprise a punched and stamped sheet metal contactor 17, a punched and stamped sheet metal actuator 18, and a coiled torsion spring 19 having divergent arms with hook ends 20 and 21 which are respectively adapted to engage said contactor and said actuator. Contactor 17 and actuator 18 are adapted to be mounted upon a common pivot pin 22 above the 20 annular shoulder 23 formed intermediate the length thereof. Thus the contactor 17 is provided with an opening 24 to provide for pivotal engagement thereof with pin 22, said flange 23 providing a bearing surface for said pivoted end of 25 the contactor. Actuator 18 is likewise provided with an opening 25 to provide for pivotal engagement thereof with pin 22 in superimposed relation to the contactor, a downwardly extending flange 25a (Fig. 3) being provided around said 30 opening 25 to space the contactor and actuator in substantially parallel planes.

Actuator 18 is preferably of somewhat elliptical contour as shown and the same is provided on opposite sides thereof with integral parallel 35 lugs 26 and 27. Contactor 17 is provided with an upwardly offset portion 28 for engagement with the stationary contact of the switch, a partially severed portion or lug 29 being located in the plane of said offset portion. The free end 30 of 40 contactor 17 is bent downwardly at a right angle to the offset portion 28 whereby the end edge 30a is normally adapted to slidably engage the bottom wall of recess 11. Lug 29 is provided with an opening 29a into which the hook end 20 of 45 spring 19 is freely insertable. Actuator 18 is also provided with an opening 18a into which the hook end 21 of spring 19 may be readily inserted without requiring any bias or compression of the spring if the actuator is turned upon pin 22 to 50 extend at substantially a right angle to contactor 17.

When the spring has been thus engaged with contactor 17 and actuator 18, the U-shaped washer 31 is moved laterally into the annular groove 55

22^a of pin 22, the arms of said washer being 5
slidable into position between the arms 26 and
27 of actuator 18. Washer 31 thus acts to prevent
upward displacement of the contactor and
actuator with respect to pivot pin 22. There-
after actuator 18 may be moved in a clockwise
direction to substantially the position shown in
Fig. 2 wherein spring 19 is positively held against
10 accidental separation from the contactor and
the actuator.

When the aforescribed parts have been as-
sembled upon pin 22, the hollow end 22^b of the
latter is inserted through opening 15 until the
flange 23 rests upon the bottom wall of recess
11. Said end 22^b projects beyond the lower face
15 of base 10 and through an opening 32^a provided
in a suitable form of wiring terminal element 32,
said end being upset over said terminal element
20 to secure the latter and said pin 22 to the base
10. As best shown in Figs. 3 and 6 the element
32 is seated in a recess formed in a boss 33 upon
the lower face of the base. As shown the end
portion 32^b of element 32 is bent to extend in
a plane at right angles to base 10, although it is
25 to be understood that all portions of said ter-
minal member may be located in a single plane
if a lesser depth of the assembled switch parts
is required.

As best illustrated in Figs. 2 and 3 the arcuate
30 portion 12^b of the recess wall accommodates the
outer edge of washer 31 whereby lateral displace-
ment thereof from pin 22 is prevented. More-
over, the edges 26^a, 27^a of the arms 26 and 27
cooperate with the vertical shoulders 12^d, 12^c
35 to limit oscillatory movement of the actuator 18.

The stationary contact of the switch comprises
a metal stud or rivet 34 the convex surface 34^a
40 of the head of which extends a predetermined
distance above the bottom wall of recess 11, and
the reduced and hollow end or shank 34^b of
45 which extends through base 10 and through the
perforation 35^a in a wiring terminal element 35
and is upset over the latter to secure said con-
tact and terminal element to the base.

At that side of the upwardly offset portion 28
45 of contactor 17 which moves into engagement
with the convex surface 34^a of the stationary
contact we preferably provide an integral up-
wardly angled lug or projection 28^a to insure
50 against stubbing of the contactor against the
stationary contact. We also preferably provide a
downwardly extending lug 28^b upon said up-
wardly offset portion to positively engage the
55 side edge of the contact to limit clockwise move-
ment of the contactor. Counterclockwise move-
ment of contactor 18 is preferably limited by
engagement thereof with the surrounding wall
of recess 11 at the point 12^x.

The snap action of contactor 17 afforded by
60 employment of spring 19 will of course be under-
stood by those skilled in the art, but it may be
pointed out (Fig. 2, for instance) that upon
counterclockwise movement of actuator 18 the
spring 19 is compressed until the end 21 of the
65 spring passes slightly to the right of a straight
line extending through the center of pin 22 and
the other end 20 of the spring, thus shifting
the direction of application of the force or energy
stored in the spring to effect snap movement of
70 contactor 17 in a clockwise direction into engage-
ment with stationary contact 34^a, such circuit
closing position being shown in full lines in Fig.
5. In like manner (Fig. 5) clockwise movement
of actuator 18 such as to carry the end 21 of
75 spring 19 to the left beyond the line extending

through pin 22 and the end 20 of the spring will
result in snap movement of contactor 17 in a
counterclockwise direction to interrupt the con-
trolled circuit.

The switch mechanism hereinbefore described
is obviously of diminutive size, which character-
istic alone renders it useful for many purposes
where the space requirements of the switch must
be reduced to a minimum. The switch parts are
so correlated as to render the same unusually 10
easy to assemble, while the construction of the
switch parts is such as to insure a long life of
the switch mechanism as a whole with no likelihood
of breakage or derangement thereof while
in service. Any suitable arrangement may be 15
provided for effecting oscillatory movement of
the actuator 18. The present switch mechanism
was, however, primarily designed for use in con-
junction with or as a switch attachment for an
electrical device such as a radio rheostat having 20
a part movable in opposite directions through an
arc or angle.

Accordingly the arms 26 and 27 of actuator 18
are provided with integral projections or ex-
tensions 26^b, 27^b which are adapted to be en- 25
gaged by an element movable arcuately in op-
posite directions to effect closing and opening of
the switch contacts. As shown in Figs. 4 and 5
the movable element may comprise a stud 36,
preferably formed of insulating material and 30
carried by the rotatable element 37 of a rheo-
stat of well known form, element 37 being at-
tached in any suitable manner to a shaft 38 which
may have a suitable knob or handle (not shown)
35 attached thereto. The rheostat as shown in-
cludes a base 39 of suitable insulating material,
said base having a rear metal cover member 40
telescoped thereonto and restrained against end-
wise separation and rotation with respect thereto
40 by means of an element 41 which is attached
in the metal cover member and is bent over the
latter (Fig. 6).

Cover member 40 is provided with a centrally
located substantially cylindrical hollow boss or 45
projection 40^a which provides clearance for the
rotatable insulating projection 36 aforesaid.
Member 40 is also provided with an ec-
centrically located opening 40^b of irregular con-
tour which is overlapped by the walls 12, 12^a 50
surrounding recess 11 in base 10. The base 10
is rigidly attached to cover member 40 as by
means of rivets or eyelets 43. With base 10 and
its assembled switch parts attached to cover
member 40 in the manner aforescribed, and 55
with the switch parts in off position as shown in
Fig. 2 the rheostatic control element 37 is turned
to that extreme position thereof wherein the end
44^a of the limiting slot 44 (shown in dotted lines
in Fig. 5) engages the element 41, with conse-
quent positioning of insulating stud 36 in the
60 dotted line position 36^x, Fig. 5. Element 41 is
then bent over cover member 40 to secure the
parts in completely assembled relation.

Thereafter movement of element 37 through a 65
relatively small angle causes engagement of ele-
ment 36 with projection 27^b on actuator 18 so
that movement of element 36 to substantially the
position shown at 36^y in Fig. 5 will result in snap
movement of contactor 17 into engagement with 70
stationary contact 34^a. Element 37 is free to
move in the same direction to its opposite ex-
treme position, wherein the other end 44^b of
slot 44 engages element 41. During the final
portion of the return movement of element 37 75

the stud 38 engages the projection 26^a on actuator 18 to stress spring 19 and effect snap movement of contactor 17 to open position at substantially the limit of such return movement.

5 What we claim as new and desire to secure by Letters Patent is:

1. In an electric snap switch, in combination, a pivot pin having an annular shoulder formed intermediate the ends thereof, a punched sheet metal contactor pivotally engaging said pin and adapted to bear against said shoulder, an actuating element pivotally engaging said pin and adapted to overlie said contactor in spaced relation to the latter, a washer removably interlocked 10 with said pin to retain all of said parts in assembled relation to each other, and a coiled torsion spring having divergent arms with hooked ends to respectively engage said contactor and said actuator, the main body of said spring lying 15 in a plane substantially parallel with and between said contactor and said actuator and the same being adapted to effect snap movement of said contactor in each direction respectively upon predetermined degrees of opposite movement of said 20 actuator.

2. In an electric snap switch, in combination, a pivot pin having an annular shoulder formed intermediate the ends thereof, a punched sheet metal contactor pivotally engaging said pin and adapted to bear against said shoulder, an actuating element pivotally engaging said pin and adapted to overlie said contactor in spaced relation to the latter, a washer removably interlocked 25 with said pin to retain all of said parts in assembled relation to each other, a coiled torsion spring having divergent arms with hooked ends to respectively engage said contactor and said actuator, the main body of said spring lying in a plane substantially parallel with and between 30 said contactor and said actuator and the same being adapted to effect snap movement of said contactor in each direction respectively upon predetermined degrees of opposite movement of 35 said actuator, an insulating base adapted to receive said pin with the switch parts assembled thereon, said pin having a hollow end portion penetrating said base and projecting therebeyond, a wiring terminal member having a perforation to accommodate said hollow end portion, said hollow end portion being upset over said terminal member to rigidly and permanently secure the latter and said switch parts to said base.

3. In an electric snap switch, in combination, a pivot pin having an annular shoulder formed intermediate the ends thereof, a punched sheet metal contactor pivotally engaging said pin and adapted to bear against said shoulder, an actuating element pivotally engaging said pin and adapted to overlie said contactor in spaced relation to the latter, a washer removably interlocked 40 with said pin to retain all of said parts in assembled relation to each other, a coiled torsion spring having divergent arms with hooked ends to respectively engage said contactor and said actuator, the main body of said spring lying in a plane substantially parallel with and between 45 said contactor and said actuator and the same being adapted to effect snap movement of said contactor in each direction respectively upon predetermined degrees of opposite movement of 50 said actuator, an insulating base adapted to receive said pin with the switch parts assembled thereon, said pin having a hollow end portion penetrating 55 said base and projecting therebeyond, a

wiring terminal member having a perforation to accommodate said hollow end portion, said hollow end portion being upset over said terminal member to rigidly and permanently secure the latter and said switch parts to said base, a second wiring 5 terminal member, a stationary contact member having an enlarged head portion for cooperation with said contactor, and said stationary contact member having a hollow end portion penetrating said base and said second terminal member and 10 upset over the latter to secure the same to said base.

4. In combination, a recessed molded insulating base, a pivot pin to be fixed thereto, a contactor and an actuator to be pivotally supported by 15 said pin, a coiled torsion spring having arms disposed in parallel planes between said contactor and said actuator and respectively attached thereto, said spring being arranged to effect snap movement of said contactor to opposite extreme 20 positions upon movement of said actuator in reverse directions respectively, and the walls of the recess being formed to limit movements of said actuator and said contactor.

5. In a switch mechanism, a casing, a spindle 25 rotatably mounted therein, an arm on said spindle projecting radially thereof and having in an eccentric relation thereto a projecting pin, an insulating base fixed to said casing and affording a wall for said casing perpendicular to the axis 30 of said spindle and parallel to the plane of movement of said arm, a pivot pin fixed to said wall afforded by said base and projecting therefrom toward the plane of said arm, and a snap switch mechanism having a contactor and an actuator 35 pivoted on said pin for pivoted movement relatively of one another, said contactor and actuator having an energy storing spring connection which effects snap movements of the former upon movement of the latter in reverse directions 40 through a given range, and said actuator having closely adjacent its pivot parts transiently engageable by said pin on said arm when said arm is moved in either direction through a given part of its range, thereby to effect reverse operations 45 of said switch.

6. In a switch mechanism, a casing, a spindle 50 rotatably mounted therein, an arm on said spindle projecting radially thereof and having in an eccentric relation thereto a projecting pin, an insulating base fixed to said casing and affording a wall for said casing perpendicular to the axis of 55 said spindle and parallel to the plane of movement of said arm, a pivot pin fixed to said wall afforded by said base and projecting therefrom toward the plane of said arm, and a snap switch mechanism having a contactor and an actuator pivoted on said pin for pivoted movement relatively of one another, said contactor and actuator having an energy storing spring connection which effects snap movements of the former upon movement of the latter in reverse directions 60 through a given range, said actuator having closely adjacent its pivot parts transiently engageable by said pin on said arm when said arm is moved in either direction through a given part of its range, thereby to effect reverse operations 65 of said switch, an externally threaded hollow bushing carried by said casing and through which said spindle is adapted to extend, and a clamping nut on said bushing to provide for one-hole mounting of said casing upon a suitable support.

7. In a snap switch mechanism of the character described, in combination, an insulating base having walls associated therewith to pro- 70

- vide a recess, a pivot pin located in said recess and rigidly attached to said base, a contactor and an actuator each having a part thereof in pivotal engagement with said pin, a stationary contact secured to said base within said recess, a wiring terminal member positioned upon the outer surface of said base and electrically connected with said contact, a coiled torsion spring having divergent arms with bent ends respectively engaged with said actuator and said contactor to effect snap movement of the latter to opposite extreme positions upon movement of the former in reverse directions respectively, said spring also acting to bias said contactor toward said base, said contactor and said contact being cooperatively formed to provide for guiding the former into proper engagement with the latter, a second wiring terminal member positioned upon the outer surface of said base, said switch mechanism being operable to alternately complete and interrupt the electrical connection between said wiring terminal members, and the walls of said recess being formed to limit movements of said actuator and said contactor.
8. In an electric snap switch, in combination, an insulating base having walls associated therewith to provide a recess, a pivot pin located within said recess and rigidly attached to said base, a contactor and an actuator to be pivotally supported by said pin, a coiled torsion spring having arms disposed in substantially parallel planes between said actuator and said contactor and respectively attached thereto, said spring being arranged to effect snap movement of said contactor to opposite extreme positions upon movement of said actuator in reverse directions respectively, and the walls of said recess being formed to limit movements of said actuator and said contactor.
9. In a switch mechanism to be operated by a pin carried eccentrically by an oscillatable member, in combination, an insulating base having in off-centered relation therewith a pivot pin fixed thereto and projecting therefrom, a snap switch mechanism having a contactor and an actuator pivoted on said pivot pin for pivotal movement relatively of one another in parallel planes, said contactor and said actuator having at one side of said pivot pin a self-expanding spring connection which effects by its expansion snap movements of the contactor upon given movements of the actuator, said actuator having closely adjacent the pivot pin parts transiently engageable by the pin on said oscillatable member when the latter is moved in either direction through a given range, thereby to effect selectively reverse operations of said switch mechanism.
10. In a switch mechanism of the character described, in combination, an insulating base having in off-centered relation therewith a pivot pin fixed thereto and projecting therefrom, a snap switch mechanism having a contactor and an actuator pivoted on said pin for pivotal movement relatively of one another in parallel planes, said contactor and said actuator having at one side of said pivot pin a self-expanding spring connection which effects by its expansion snap movements of the contactor upon reverse movements of the actuator, a pivoted operating arm overlying said actuator, said arm being oscillatable in a plane parallel to the plane of movement of said actuator and having a pin extending therefrom eccentrically and perpendicularly thereof, and said actuator having closely adjacent the pivot pin parts transiently engageable by the pin on said oscillatable member when the latter is moved in either direction through a given range, thereby to effect selectively reverse operations of said switch mechanism.
11. In a switch mechanism of the character described, in combination, a one-piece insulating base, a pivot pin having a portion thereof penetrating said base and rigidly attached thereto, a contactor and an actuator each having a part thereof in pivotal engagement with said pin for support by the latter, a stationary contact secured to the inner surface of said base, a wiring terminal member positioned upon the outer surface of said base and electrically connected with said contact, a self-expanding spring interposed between said actuator and said contactor at one side of said pivot pin, said spring being arranged to effect by its expansion snap movements of said contactor to opposite extreme positions upon movements of said actuator in reverse directions respectively, said spring also acting to bias said contactor toward the inner surface of said base, said contactor and said contact being cooperatively formed to provide for guiding the former into proper engagement with the latter, and a second wiring terminal member positioned upon the outer surface of said base, said switch mechanism being operable to alternately complete and interrupt an electrical connection between said wiring terminal members.
12. In a switch mechanism of the character described, in combination, an insulating base, a pivot pin having a portion thereof penetrating said base and rigidly attached thereto, a contactor and an actuator each having a part thereof in pivotal engagement with said pin, a stationary contact secured to the inner surface of said base, a wiring terminal member positioned upon the outer surface of said base and electrically connected with said contact, a self-expanding spring interposed between said actuator and said contactor at one side of said pivot pin, said spring being arranged to effect by its expansion snap movement of said contactor to opposite extreme positions upon movement of said actuator in reverse directions respectively, said spring also acting to bias said contactor toward the inner surface of said base, said contactor and said contact being cooperatively formed to provide for guiding the former into proper engagement with the latter, a second wiring terminal member positioned upon the outer surface of said base, said switch mechanism being operable to alternately complete and interrupt an electrical connection between said wiring terminal members, said actuator having a pair of spaced arms, and an operating member movable in opposite directions throughout a predetermined range, said operating member having a transient lost motion driving connection with said actuator to provide for closed-circuit and open-circuit operation of said switch mechanism during movements of said operating member in reverse directions respectively through a relatively small portion of its range.
13. An electric snap switch of relatively small dimensions, comprising a molded insulating base having a relatively shallow recess extending throughout the major portion of one face thereof, a pair of wiring terminal members positioned upon the opposite face of said base, a pivot pin at one end of said recess, said pin having a shovelled hollow end penetrating said base and one of said terminal members and riveted over the latter to secure said parts to each other, a sta-

tionary contact at the other end of said recess, said contact having a shouldered hollow end penetrating said base and the other terminal member and riveted over the latter, a punched sheet metal contactor pivotally mounted on said pin, an actuating element also pivotally mounted on said pin, and a coiled torsion spring having arms the hooked end portions of which are respectively engaged with said actuator and said contactor to effect snap movements of the latter into and out of engagement with said contact upon given oppositely directed movements of the former.

14. An electric snap switch of relatively small dimensions, comprising a molded insulating base having a relatively shallow recess extending throughout the major portion of one face thereof, a pair of wiring terminal members positioned upon the opposite face of said base, a pivot pin at one end of said recess, said pin having a shouldered hollow end penetrating said base and one of said terminal members and riveted over the latter to secure said parts to each other, a stationary contact at the other end of said recess, said contact having a shouldered hollow end penetrating said base and the other terminal member and riveted over the latter, a punched sheet metal contactor pivotally mounted on said pin, an actuating element also pivotally mounted on said pin, a coiled torsion spring having arms the hooked end portions of which are respectively engaged with said actuator and said contactor to effect snap movements of the latter into and out of engagement with said contact upon given oppositely directed movements of the former, a U-shaped washer laterally engaged with said pin to retain said actuator and said contactor in assembled relation, the wall of said recess being formed to prevent displacement of said washer, and said actuator having spaced lugs formed thereon to provide a lost motion driving connection between the same and a suitable operating member.

15. An electric snap switch of relatively small dimensions, comprising a molded insulating base having a relatively shallow recess extending throughout the major portion of one face thereof, a pair of wiring terminal members positioned upon the opposite face of said base, a pivot pin at one end of said recess, said pin having a shouldered hollow end penetrating said base and one of said terminal members and riveted over the latter to secure said parts to each other, a stationary contact at the other end of said recess, said contact having a shouldered hollow end penetrating said base and the other terminal member and riveted over the latter, a punched sheet metal contactor pivotally mounted on said pin, an actuating element also pivotally mounted on said pin, a coiled torsion spring having arms the hooked end portions of which are respectively engaged with said actuator and said contactor to effect snap movements of the latter into and out of engagement with said contact upon given oppositely directed movements of the former, a U-shaped washer laterally engaged with said pin to retain said actuator and said contactor in assembled relation, the wall of said recess being formed to prevent displacement of said washer, said actuator having spaced lugs formed thereon to provide a lost motion driving connection between the same and a suitable operating member, and a metal shell or cover member to which said insulating base is rigidly attached, said shell

having an opening to provide clearance for said lost motion driving connection.

16. In an electric snap switch, in combination, an insulating base member having a recess, a pivot pin secured to said base and projecting upwardly from the bottom wall of said recess, a contact member secured to said bottom wall and having a convex end portion projecting upwardly therefrom, a punched and stamped sheet metal contactor having one end portion thereof pivotally supported by said pin, the other end portion of said contactor being offset upwardly to normally lie in a plane slightly below the convex end of said contact, said offset portion having an upwardly angled edge to facilitate engagement thereof with said contact, and said offset portion also having a downwardly extending lug cooperable with said contact to limit movement of said contactor in one direction.

17. In an electric snap switch, in combination, an insulating base member having a recess, a pivot pin secured to said base and projecting upwardly from the bottom wall of said recess, a contact member secured to said bottom wall and having a convex end portion projecting upwardly therefrom, a punched and stamped sheet metal contactor having one end portion thereof pivotally supported by said pin, the other end portion of said contactor being offset upwardly to normally lie in a plane slightly below the convex end of said contact, said offset portion having an upwardly angled edge to facilitate engagement thereof with said contact, said offset portion also having a downwardly extending lug cooperable with said contact to limit movement of said contactor in one direction, said contactor being engageable with a side wall of said recess to limit movement thereof in the reverse direction, and spring means for effecting snap movement of said contactor in opposite directions respectively.

18. In an electric snap switch, in combination, an insulating base member having a recess, a pivot pin secured to said base and projecting upwardly from the bottom wall of said recess, a contact member secured to said bottom wall and having a convex end portion projecting upwardly therefrom, a punched and stamped sheet metal contactor having one end portion thereof pivotally supported by said pin, the other end portion of said contactor being bent downwardly at right angles to the main body thereof whereby its edge is adapted for sliding engagement with said bottom wall, the intermediate portion of said contactor being offset upwardly to normally lie in a plane slightly below the convex end of said contact, said offset portion having an upwardly angled edge to facilitate engagement thereof with said contact, said offset portion also having a downwardly extending lug cooperable with said contact to limit movement of said contactor in one direction, said contactor being engageable with a side wall of said recess to limit movement thereof in the reverse direction, and spring means for effecting snap movement of said contactor in opposite directions respectively, said spring means also acting to bias said contactor toward said bottom wall of the recess.

19. In combination, a recessed molded insulating base, a contactor oscillatably supported within said recess, an actuator also oscillatably supported within said recess in upwardly offset relation to the bottom wall of the latter, said actuator having spaced lugs adapted for transient

engagement alternately by an oscillatable operating member of suitable form, a stationary contact member located within said recess, a coiled spring interposed between the free end of said contactor and said actuator to effect snap movements of said contactor into and out of engagement with said stationary contact upon movements of said actuator in reverse directions respectively, a plurality of wiring terminal members secured to said insulating base and exposed on the outer surface of the latter, and means comprising a plurality of metal eyelets for attaching said insulating base at spaced points to an electrical device in a relation to provide for concealment of said recess and the switch parts located therewithin.

20. An electric snap switch of relatively small dimensions, comprising a molded insulating base having a relatively shallow recess extending throughout the major portion of one face thereof, a contactor and an actuator pivotally supported within said recess, said actuator having spaced lugs formed thereon to provide a lost motion driving connection between the same and a suitable operating member, a spring interposed between the free end of said contactor and said actuator to effect snap movements of the former in reverse directions upon movements of the latter in opposite directions respectively, the walls of said recess being adapted to limit the aforementioned movements of said contactor and said actuator, and means for attaching said insulating base to a suitable support.

21. In combination, a recessed molded insulating base, a terminal member positioned upon the outer surface of said base, a pivot pin having a portion thereof penetrating said base and said terminal member and upset over the latter to secure said parts to each other, a contactor and an actuator to be pivotally supported by said pin, a stationary contact secured within said recess and having the contact surface thereof spaced upwardly from the bottom wall of said recess, a coiled spring interposed between said actuator and said contactor, said spring being arranged to effect snap movement of said contactor to opposite extreme positions upon movement of said actuator in reverse directions respectively, said spring also acting to bias the free end of said contactor to a plane slightly below said contact surface, said contactor having an upwardly angled lug at the edge thereof adjacent to said contact to guide the free end of the former into engagement with said contact surface and the walls of said recess being formed to limit movements of said actuator and said contactor.

22. An electric snap switch comprising an insulating base having a pair of wiring terminal members positioned in spaced relation to each other upon one face thereof, a pivot pin having a hollow end portion penetrating said base and one of said terminal members and upset over the latter to secure said parts in assembled relation, a punched and stamped sheet metal contactor pivotally supported upon the opposite face of said base by said pivot pin, a stationary contact having a convex head portion positioned upon the last mentioned face of said base and having a hollow end penetrating the latter and the other of said terminal members and upset over the latter to secure said parts in assembled relation, an actuating element also pivotally supported upon said last mentioned face of said base, and a coiled torsion spring having divergent arms with hooked end portions to be respec-

tively engaged with said actuator and said contactor to effect snap movements of the latter into and out of engagement with said stationary contact upon given oppositely directed movements of the former.

23. In an electric snap switch, in combination, an insulating base, a pair of wiring terminal elements positioned in spaced relation to each other on one face of said base, a stationary contact comprising a rivet having a head portion positioned upon the opposite face of said base, said rivet having a hollow shank penetrating said base and one of said terminal elements and upset over the latter to rigidly secure said parts in assembled relation, a punched and stamped sheet metal contactor pivotally supported upon the last mentioned face of said base, the pivotal supporting means for said contactor including a pin having a hollow end portion penetrating said base and the other of said terminal elements and upset over the latter to rigidly secure said parts in assembled relation, an actuating element for said contactor also pivotally supported upon said last mentioned face of said base, a coiled torsion spring having divergent arms with bent ends to respectively engage said actuator and said contactor to effect snap movements of the latter into and out of engagement with said stationary contact upon given oppositely directed movements of the former, said spring acting to bias the free end portion of said contactor toward said base whereby said free end portion is normally movable in a plane slightly below the upper surface of said contact, and said free end portion having an upwardly angled edge to facilitate sliding engagement thereof with said contact.

24. In combination, an electrical resistance varying device having a member movable throughout a relatively wide range with reference to a given axis, a projecting element mounted upon said member eccentrically of said axis, a relatively shallow recessed molded insulating base, a snap switch mechanism located within the recess in said base and including an oscillatable actuating element, a metal cover member for said resistance varying device attached thereto directly, means penetrating said cover member and said base at a plurality of spaced points whereby the latter is rigidly secured to the former in a relation to provide for concealment of the switch parts with said actuating element oscillatable in a plane parallel to the plane of movement of said projecting element, said cover member having an opening therein to provide clearance for part of said actuating element, and said projecting element having a transient lost motion driving connection with said part of said actuating element to provide for operation of the switch parts to closed and/or open-circuit position during movement of said movable member in reverse directions respectively through a relatively small portion of its range.

25. In combination, a recessed molded insulating base, a terminal member positioned upon the outer surface of said base, a pivot pin having a portion thereof penetrating said base and said terminal member and having a part in clamping engagement with the latter, a contactor and an actuator each having a part thereof in pivotal engagement with said pin, a stationary contact secured within said recess and having a surface thereof spaced upwardly from the bottom wall of said recess, a second terminal member positioned upon the outer surface of

- 5 said base and electrically connected with said contact, a coiled spring interposed between said actuator and said contactor, said spring being arranged to effect snap movement of said contactor to opposite extreme positions upon movement of said actuator in reverse directions respectively, said spring also acting to bias the free end of said contactor to a plane slightly below said contact surface, said contactor and said 10 contact being cooperatively formed to provide for guiding the free end of the former into engagement with said contact surface, and the walls of said recess being formed to limit movements of said actuator and said contactor.
- 15 26. In a combined volume control and switch, in combination, an assembly comprising a resistor, wiring terminals, means including a rotatable member to vary a circuit connection of said resistor and a supporting base for said resistor, said wiring terminals and said means, another assembly comprising a switch, wiring terminals and a supporting base for said switch and terminals, said rotatable member having an operative connection with said switch, the connection 20 between said rotatable member and said switch being of a transient character and comprising a pivoted element of said switch assembly having its pivotal axis parallel to and spaced laterally from the axis of rotation of said rotatable member, said pivoted element having relatively close to its pivot means extended axially of said element for transient engagement by said rotatable member, and a housing including the bases of said assemblies to support and fully enclose 25 said resistor, substantially all of its said circuit varying means, said switch and said operative connection, said rotatable member extending outside of said housing.
- 30 27. The combination with an electrical resistance varying device having a member rotatable to opposite extreme positions, of a projecting element mounted eccentrically upon said member, a metallic cover member for said resistance varying device directly attached thereto, said cover member having an opening formed in its end wall, a relatively shallow recessed molded insulating base member adapted to overlie said opening and rigidly secured to said cover member, and a snap switch mechanism carried in its entirety by said base member and enclosed thereby, said switch mechanism including a pivoted actuating element with which said projecting element has transient driving engagement in different positions of said rotatable member where- 35 by operation of said switch mechanism is effected, said actuating member having its pivotal axis parallel to the axis of said rotatable member.
- 40 28. In a combined volume control and switch unit, in combination, an assembly comprising a resistor, wiring terminals, means including a rotatable member to vary a circuit connection of said resistor and a supporting base for said resistor, said terminals and said means, another assembly comprising a switch, wiring terminals and a supporting base for said switch and latter terminals, said switch including a pivoted actuating element movable in a plane perpendicular to the axis of said rotatable member and said rotatable member having offset laterally from its 45 axis a projection for transient engagement with said actuating element of said switch and a built-up housing for said assemblies, said housing including the bases of said assemblies and also in- 50 cluding a metal wall interposed between said two assemblies and having formed in it an opening, said switch actuating element having rigid means extending through said opening in said metal wall relatively close to the pivot of said element to be transiently engaged by said projection of said rotatable member beyond said metal wall, said rotatable member being in part enclosed by said housing but having a part extending outside of said housing. 55
- 10 29. The combination with an electrical resistance varying device, said device having a member rotatable in opposite directions between extreme positions to vary the value of active resistance, of a projecting element mounted upon said member and movable thereby through an arcuate path, a stamped sheet metal cover member for said resistance varying device, said cover member comprising as a unitary part thereof a wall having an opening formed therein and arranged in unsymmetrical relationship to the contour thereof, a relatively shallow recessed molded insulating base, said base being fitted closely against said wall and being rigidly attached thereto in a relation to overlie said opening, and a snap switch mechanism having the switch parts thereof located within the recess in said base member and having the wiring terminal parts thereof exposed upon the outer surface of said base, said switch mechanism including an oscillatable actuating element extending into said cover member through said opening and having a pair of spaced upstanding arms with which said projecting element has transient driving engagement in different positions of said 20 rotatable member whereby operation of said switch mechanism is effected. 25
- 30 30. The combination with a rheostat having a shaft rotatable in opposite directions between limits to effect variation in the value of active resistance, a stud mounted eccentrically of the axis of said shaft and movable by the latter in an arcuate path, a one-piece cup-shaped stamped sheet metal cover secured to said rheostat, said cover having an opening formed in a wall there- 35 of and located eccentrically with respect to the contour of said cover, a relatively small and relatively shallow recessed molded insulating base, the recessed face of said base being snugly fitted against the outer surface of said cover and being rigidly attached thereto in a relation to overlie said opening, and a snap switch mechanism having the switch parts thereof located within the recess in said base and having the wiring terminal parts thereof exposed upon the outer surface of said base, said switch mechanism includ- 40 ing an oscillatable contactor and an oscillatable actuating element therefor with a spring member interposed therebetween, a pivot member common to said contactor and said actuating ele- 45 ment, said actuating element extending into said cover through said opening and having a pair of spaced upstanding arms with which said stud has transient driving engagement in different 50 rotary positions of said shaft whereby operation of said switch mechanism is effected, the walls of the recess in said base acting to limit oscillatory movements of said contactor and said actuating element in opposite directions respec- 55 tively. 60
